UNITED STATES PATENT OFFICE

GUY R. SIGMAN, OF KEARNEY, NEBRASKA

ADVERTISING CABINET

Application filed May 28, 1928. Serial No. 281,310.

This invention relates to advertising cabinets, and its general object is to provide a cabinet of the changeable exhibitor type, that is primarily designed for use for display purposes in front of motion picture theaters and the like for advertising the pictures and other features of the theater, as well as business establishments, firms and the like in the neighborhood of the theater.

10 A further object of the invention is to provide an advertising cabinet adapted for displaying any subject matter including merchandise, in a manner whereby it will attract the casual observer.

15 Another object of the invention is to provide an advertising cabinet of the character set forth, that is illuminated, motor operated, is simple in construction, inexpensive to manufacture and efficient in operation and service.

20 This invention also consists in certain other features of construction and in the combination and arrangement of the several parts, to be hereinafter fully described, illustrated in the accompanying drawings and specifically 25 pointed out in the appended claims.

In describing my invention in detail, reference will be had to the accompanying drawings wherein like characters denote like or corresponding parts throughout the several 30 views, and in which:

Figure 1 is a front elevation of the advertising cabinet forming the subject matter of the present invention.

Figure 2 is a vertical sectional view taken 35 longitudinally therethrough and showing parts in elevation.

Figure 3 is a sectional view taken approximately on line 3—3 of Figure 2, looking in the direction of the arrows.

40 Figure 4 is a fragmentary detail view illustrating the application of a carrier for the purpose of displaying merchandise and the like.

45 Referring to the drawings in detail, the reference numeral 1 indicates the base of the cabinet which may be of any ornamental design and have casters secured thereto in any well known manner, whereby the cabinet can be moved from place to place in an easy and 50 expeditious manner as will be apparent.

The body of the cabinet as shown is substantially square in cross section and includes front and rear walls indicated respectively by the reference numerals 2 and 3, and side walls indicated respectively by the reference numerals 4 and 5. These walls have their confronting edges secured together in any well known manner and have their lower edges secured to the base accordingly.

55 The upper portions of the front and rear walls 2 and 3 are flared outwardly as at 7, and these flared portions are cut-away to provide slots 8 which form sight openings covered by glass or other transparent material 9 which are received in frames 10 having guide flanges 11 for that purpose as well as to accommodate pictures and the like 12 disposed to the rear of the glass. By this construction, it will be obvious that the pictures are arranged at an inclination as best shown in Figure 2 whereby 60 they can be readily observed.

65 A top 13 has formed on its outer edges a depending flange 14 which is secured to the upper edges of the flared portions as well as the upper edges of the side walls 4 and 5, and 70 said top is inclined upwardly toward its center so that it will shed water as will be apparent. The top is centrally provided with an opening having an annular flange 15 surrounding the same and is adapted for the 75

80 purpose of receiving a shaft 16 which extends vertically therethrough and has an upper threaded end threadedly receiving a collar 17 formed with and depending from the top of a housing 18 which includes vertical walls 85 having sight openings formed therein for the purpose of displaying signs 19 which are detachably secured in guide flanges 20 formed in the walls of the housing and the walls are arranged in spaced relation with respect to the top and the annular flange 15 so that the housing may be rotated through the medium of the shaft 16 which has secured to its lower end a beveled gear 21 meshing with a like gear 22 fixed to the shaft of an electric motor 24.

85 The shaft 16 is provided with a bearing 25 having arms 26 formed therewith and secured to the underside of the top 13, as best shown in Figure 2. Secured to the shaft 16 is a collar 27 which is disposed in engagement 90

with the bearing 25 for supporting the shaft as will be apparent.

The motor is secured to and supported by a cross member 28 having its ends secured to the front and rear walls 2 and 3 adjacent the upper end of the cabinet, as best shown in Figures 2 and 3 of the drawings. Formed with the shaft of the motor is an annular groove providing a pulley 29 which has trained thereabout a belt 30. The belt is received by a pulley 30' as best shown in Figure 3. Secured in the side walls 4 and 5 and arranged in pairs are stub shafts 31 while secured in said cabinet is a U-shape frame 31' and pinions 32 are fixed to the ends of a shaft 32' mounted for rotation in the arms of the frame 31'. The shaft 32' has secured thereto the pulley 30'. Each of the stub shafts 31 have sprocket wheels 33 secured thereon, and also fixed to these stub shafts 31 are gears 33' meshing with the pinions 32. By this construction, it will be apparent that the sprocket gears 31 are operated by the motor 24.

Arranged adjacent the bottom of the cabinet and mounted for slidable adjustment in slots 34 formed in the side walls thereof are stub shafts 35 which have secured thereto sprockets 36. The sprockets 36 cooperate with the sprockets 33 for receiving sprocket chains 37, and by this arrangement, it will be apparent that the chains are driven through the instrumentality of the sprockets 33 rotated by the gears 33', while the remaining sprockets act as guides for the chains.

The sprocket chains have secured thereto at equi-distantly spaced intervals with respect to each other, the ends of a plurality of rods 38 which are adapted to receive the hooks 39 of frames 40. The rods have arranged thereon a plurality of spacing sleeves 41 and the hooks are disposed between some of these sleeves as best shown in Figure 3 of the drawings so as to prevent longitudinal movement of the frame with respect to the rods and thereby prevent the frames from coming in contact with the sprocket chains.

The sleeves may be of various sizes if desired so as to accommodate the hooks regardless of their arrangement with respect to the frames. The rods are disposed a suitable distance apart to accommodate the frames and the space between the frames may be covered with fringe or like ornamental material 42. This material 42 also covers the hooks as will be noted upon inspection of Figure 1. Any type of display card may be carried in the frames 40 and I have shown pictures 43 in some of the frames and cards 44 having advertising indicia thereon in other of the frames. The pictures are adapted to advertise features shown at the theaters displaying the cabinet while the indicia on the cards advertise business establishments, firms and the like in the neighborhood of the theaters.

The front and rear walls of the cabinet are

provided with sight openings 45 which extend from adjacent the top thereof and terminate adjacent the bottom as clearly shown in Figures 1 and 2 so that all of the frames carried by the respective vertical runs of the chains can be displayed through the sight openings.

In Figure 4 I have illustrated a carrier for merchandise and the like and which includes a base 46 having secured thereto and rising from adjacent the corners thereof converging uprights 47.

The uprights which extend from one of the corners terminate at their upper ends in hooks 48 adapted to be received by the rods 38 so that the carriers can be secured to the rods 38 in the same manner as the frames for the purpose of displaying merchandise and the like upon the base 46 of said carriers as will be apparent.

The cabinet as well as the housing 18 has arranged therein electric light bulbs 49 which of course are in connection with a suitable source of electrical energy and the bulbs of the cabinet are disposed above and below the sight openings 45, while the bulbs for the housing are arranged on the flange 15 of the top 13 as shown in Figure 2. The bulbs of the cabinet are provided with reflectors 50 which are arranged at an inclination so as to deflect the rays of light from the bulbs toward the frames.

The side walls are each provided with transversely disposed sight openings 51 for the purpose of displaying cards or pictures 52 and these cards and pictures 52 are likewise detachably arranged in frames 53.

Vertically secured in said cabinet through the instrumentality of screws or the like 54 passing through apertured ears 55 formed therewith is a reflector 56 which may be formed from white sheet metal, but in any event is adapted to reflect the rays of illumination toward the pictures and advertising cards which may be semi-transparent whereby the rays of illumination will pass therethrough as will be apparent.

The cabinet shown is provided with casters at one side of its bottom, while adjustable rods providing feet are secured at the opposite side so that the cabinet can be made level on inclined sidewalks and the like in front of buildings. Secured to the sides of the cabinet are bracket shelves 57 to accommodate vending machines and the like.

One side wall of the cabinet is hingedly secured with an appropriate latching means therefor, and by this construction, it will be apparent that access may be had to the interior of the cabinet for any purpose desired.

While I have shown the cabinet arranged with frames for receiving picture cards and advertising matter for the purpose of advertising theaters, and these picture cards are disposed in the frames in pairs so that they may be viewed through either of the sight open-

ings, when the cabinet is adapted for the purpose of advertising business houses and the like, the frames 40 are to be replaced by the merchandise carriers, as shown in Figure 4. Of course some of the frames may be retained for receiving price cards and the like.

From the above description and disclosure of the drawings, it will be obvious that I have provided an advertising cabinet of the changeable exhibitor type, that is adapted for displaying any subject matter including merchandise, in a manner whereby the subject matter will attract the attention of a casual observer, due to the constant movement thereof.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. An advertising cabinet of the character described comprising a base, front, rear and side walls secured to and rising from said base, slotted outwardly flared upper ends formed with said front and rear walls, a top secured to the upper edges of the flared upper ends and the upper ends of the side walls respectively, means for supporting advertising matter to be seen through the slots in the flared upper ends, a housing mounted for rotation above said top, advertising matter carried by said housing and means arranged in the cabinet for rotating said housing.

2. An advertising cabinet of the character described comprising a base, front, rear and side walls secured to and rising from said base, said front and rear walls being provided with elongated sight openings extending from adjacent their upper edges and terminating adjacent the lower ends thereof, stub shafts secured in the side walls and being arranged in pairs, stub shafts having their ends adjustably mounted in slots disposed in said side walls adjacent the bottom thereof, sprocket wheels secured to said stub shafts, chains trained about said sprocket wheels, means for rotating some of said sprocket wheels for moving the chains accordingly, display carrying means detachably associated with said chains and being arranged to show through the sight openings, and one of said side walls being hinged whereby access may be had to the interior of said cabinet.

3. An advertising cabinet of the character described comprising a base, front, rear and side walls secured to and rising from said base, said front and rear walls being formed with sight openings, display means for merchandise and advertising matter mounted

for movement and arranged to show through said sight openings, means for moving the display means, illuminating means in said cabinet, inclined reflectors disposed adjacent said illuminating means, and a reflecting means vertically and centrally arranged in said cabinet and cooperating with the inclined reflectors for reflecting the rays of illumination toward the display means for illuminating merchandise and advertising matter carried thereby.

In testimony whereof I affix my signature.

GUY R. SIGMAN.
